BELT WITH GARMENT HOLDING CLAMPS

Charles K. Seid, Woodmere, N. Y.

Application December 1, 1948, Serial No. 62,856

3 Claims. (Cl. 2—312)

1

This invention relates to clasps, and particularly to a multiple use clasp adapted for holding folded or unfolded fabrics or other articles in relation to the object to which the clasp may be secured.

The object of the invention is to provide an improved clasp including a base and a spring actuated clasping tongue which, may be positioned at any effective angle to the base, or parallel thereto, and at any distance from the base within the capacity of the device.

A further object of the invention is to provide a clasp as mentioned which may be manufactured in various sizes and proportions to adapt the device to divers uses.

Other objects will appear hereinafter.

The invention consists generally in a clasp comprising a base or body portion, a spring actuated presser or clasping tongue, and a spring actuated intervening link pivotally connected to both the body portion and the tongue, whereby the tongue may be positioned at any distance from the body portion within the limits of the device and at any angle to the body in order that the pressure of the tongue may be exerted uniformly across the material or object interposed between the base and tongue, or with greater pressure at one end thereof than at the other.

The invention further consists in various details of construction and arrangement of parts as will be fully described and particularly pointed out in the claims.

The invention will be more readily understood by reference to the accompanying drawings forming a part of this application and in which

Figure 1 is a plan view of an embodiment of the invention, illustrating the same as applied to a belt,

Figure 2 is a longitudinal section thereof on substantially the line 2—2 of Figure 1, the tongue and connecting link being shown in elevation,

Figure 3 is a view illustrating a use of the invention when applied to a belt,

Figure 4 is a longitudinal section of a clasp embodying the invention as applied to a table top or the like,

Figure 5 is a detail longitudinal section upon an enlarged scale, and taken on the line 5—5 of Figure 6, and

Figure 6 is a transverse section on the line 6—6 of Figure 5.

Referring to the drawings, 10 indicates the base of the clasp which is preferably an elongated member provided in its outer face with a shallow recess 11 extending the greater portion of the

2

length of the base to accommodate a clasping tongue 12 when the same is in retracted or inoperative position. The recess 11 is substantially the depth of the thickness of the tongue 12 and extends throughout the major portion of the length of the device. At one end of the said recess is an aperture 13 preferably the width of said recess 11 and extending through said body.

Within said aperture 13 is hingedly mounted a link 15 on a transverse pin 16 fixed in the base member 10 below the plane of the outer face thereof and spanning the aperture 13. The link 15 corresponds in width to that of the aperture 13, and at the free end thereof is provided with ears 17 in which is mounted a pin 18 the ends of which extend beyond the ears 17 into lugs 19 depending from the tongue 12. The lugs 19 are spaced from the adjacent end of the tongue providing a rearwardly extending portion 12' the purpose of which will appear hereinafter. When the tongue 12 is retracted within the recess 11, the link 15 will lie beneath the tongue and entirely within the aperture 13, as illustrated in Fig. 4 of the drawings, the side walls of the recess being notched to receive the lugs 19.

Coiled about the pin 18 between the ears 17 is a spring 21 the extended ends 22 and 23 of which are seated in longitudinal grooves 24 and 25 formed in the tongue extension 12' and the link 15 respectively. A flat spring 27 having one end 27' thereof fixed in the base 10, is formed with a concavely curved portion 27'' at its free end which engages beneath the preferably squared lower end 15' of the link 15. The curved portion 27'' is substantially concentric with the pin 16 for the major portion of its extent so that said spring will hold the link firmly in both the fully elevated position shown in full lines in Fig. 5, and in fully folded position as indicated at 15^a in the same figure, and in full lines in Fig. 4. When in an intermediate position, as illustrated in dotted lines in Fig. 5, the spring 27 exerts a turning moment upon the link which adds to the pressure of the tongue 12 upon the material or object between the tongue and the base, particularly adjacent the hinge.

When the device is fully folded or collapsed, the tongue 12 lies within the recess 11 and preferably with the outer face thereof flush with the adjacent outer face of the body. Preferably, the tongue 12 terminates a short distance from the end of the recess, as indicated at 11^a in Fig. 1, to facilitate raising the tongue when desired.

It should be noted that the extended portion 12' of the tongue rests against the upper face of

the link 15 when in folded position. By this construction, when the tongue 12 is raised, as indicated by the dotted lines 12^a in Fig. 5 the link 15 will also be raised. After the link 15 has been raised sufficiently, and the material to be clasped has been placed in position, the tongue is released and the spring 21 will swing the tongue into position to hold the material.

The clasp above described is adapted for manifold uses, by varying the size of the device to suit the particular purpose to be attained and by varying the relative proportions of the tongue and link; all of which are contemplated and are within the scope of the invention.

In Figures 1 to 3 of the drawings the device has been illustrated as applied to a belt 30, and as such is adapted to hold back the front edges of a coat as shown in Figure 3, which is of great convenience to protect the garment when the wearer is seated at a lunch counter, at a work table, or under various conditions. When the device is applied to a belt the base 10 is preferably embedded therein with its outer face substantially flush with the outer surface of the belt and remote from the belt buckle, as illustrated in Figure 2.

The device may also be applied to a sewing machine or other work table top 31 to hold the work while stitching or cutting; and when so used the ability to angularly adjust the link and tongue is of particular advantage, as when the material being worked upon is folded, the tongue may be adjusted to engage the material remote from the fold and hold the same firmly without creasing at the fold.

It is obvious that the device may be designed for use with either men's or women's wearing apparel either to support or to hold a garment in place; also to attach collars, cuffs or other trimmings to a garment or to hold neckties or the like in the desired position.

The device may also be used in place of the usual tie-backs for draperies, and to hold the pleats in said draperies without the necessity of stitching.

Also, it may be adapted for industrial use where a clamping and tension action is desired, accompanied by a quick release which may be had by pressure, manually or otherwise, on the extended end 12' of the tongue 12, or by raising the tongue 12 upon lifting the work against the tension of the spring 21, the tension of which may be designed for the particular purpose for which the device is to be used. By varying the lengths of the link 15 and tongue 12, and the tension of the springs 21 and 27, the device may be designed for many uses either as a portable or fixed clasp.

Among further uses the device may be used to hold sheets of paper or other materials where quick release of one or more sheets may be desirable, such as in writing pads, notebooks, wallets et cetera; or as a pocket clasp for fountain pens or for pencils.

In any of the uses to which the invention is to be put, the device may be designed either to crease or not to crease the work, as desired.

I claim:

1. A belt having the usual buckle and free ends, in combination with a pair of clasps fixed thereto in spaced relation from said ends respectively, each of said clasps comprising an elongated base, a link hinged at its inner end to the base adjacent the forward end thereof, a clasping tongue hinged to the outer end of said link and extending rearwardly therefrom to clasp the forward edges of a coat, a spring interposed between said link and said tongue and coiled around the hinged connection of the link and tongue, and a flat spring attached at one end to said base and its other end engaging under the inner end of said link.

2. A belt, in combination with a pair of clasps as set forth in claim 1 in which the base of each clasp is embedded in the belt with the outer faces thereof substantially flush with the outer surface of the belt and the springs tending to force the tongue into operative clamping relation with said base.

3. A clasp comprising an elongated base, a link, a hinged connection adjacent the inner end of said link and connecting said link to said base on an axis below the outer surface of said base and adjacent one end of said base, an elongated clasping tongue, a hinged connection between the outer end of said link and said tongue, said tongue extending toward the end of said base remote from the first said hinged connection, a spring interposed between said link and said tongue and coiled around the hinged connection between said link and said tongue, said spring constantly tending to force the outer end of said tongue toward said base, a flat spring attached at one end to said base and the other end thereof engaging under the inner end of said link to yieldingly hold said link in an optional angular position, and an extension on said tongue projecting beyond the last said hinged connection in the opposite direction from said tongue and adapted to engage the adjacent face of said link when said tongue is in substantial alignment with said link, whereby said link may be raised thereby simultaneously with said tongue.
